US00D950577S

(12) **United States Design Patent** (10) **Patent No.:** **US D950,577 S**
(45) **Date of Patent:** **** May 3, 2022**

(54) **DISPLAY SCREEN OR PORTION THEREOF
WITH GRAPHICAL USER INTERFACE**

(71) Applicant: **Lutron Technology Company LLC**,
Coopersburg, PA (US)

(72) Inventors: **Manisha Dahiya Baluja**, Lansdale, PA
(US); **John N. Callen**, Center Valley,
PA (US); **Duheng Liang**, Bethlehem,
PA (US); **Shenchi Tian**, Easton, PA
(US)

(73) Assignee: **Lutron Technology Company LLC**,
Coopersburg, PA (US)

(**) Term: **15 Years**

(21) Appl. No.: **29/749,201**

(22) Filed: **Sep. 3, 2020**

Related U.S. Application Data

(63) Continuation of application No. 29/660,144, filed on
Aug. 17, 2018, now Pat. No. Des. 898,041, which is a
continuation of application No. 29/590,902, filed on
Jan. 13, 2017, now abandoned.

(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The sole FIGURE shows a display screen or portion thereof with graphical user interface showing our new design.

The peripheral dashed broken lines illustrate a display screen or portion thereof, and form no part of the claimed design.
